UNITED STATES PATENT OFFICE.

BARNEY BERNARD, OF DETROIT, MICHIGAN.

HOOD.

1,263,514.

Specification of Letters Patent. Patented Apr. 23, 1918.

Application filed October 18, 1917. Serial No. 197,190.

To all whom it may concern:

Be it known that I, BARNEY BERNARD, a citizen of the United States, and residing at Detroit, in the county of Wayne and State 5 of Michigan, have invented a new and Improved Hood, of which the following is a specification.

The invention has reference to sectional sheet metal hoods for inclosing the engines 10 of automobiles, and relates particularly to the construction of those portions of the hood in and around the joint between the sections of the top.

The connections between the top sections, 15 so far as I am aware, have heretofore usually included a longitudinally extending hinge rod or rods independent from the sections themselves and coöperating with hinge lips or coils thereon, but this construction has 20 been relatively expensive and has prevented the sections from being readily detached from one another. In those cases wherein the rod or rods have been dispensed with, some other separate member or members has 25 been employed.

The present invention consists in a hood having complementary top sections which in themselves and without the use of separate connecting elements are so constructed that, 30 when one of the sections is tilted upwardly in respect to the other, it may be removed by simply drawing longitudinally along the pivotal axis, said sections also being interlocked with one another when the sections 35 are in normal position. It also consists in hood sections having rigid therewith at the ends thereof reversely arranged upwardly and laterally offset pintles and sockets forming detachable pivotal connections, the up- 40 per surface presenting no upwardly extending projections along the line of the seam. Again, it consists in a hood section having beneath its longitudinal edge a bar to which the sheet metal of the hood is welded, said 45 bar having at one end beyond the sheet metal an offset pindle and at its other end an offset socket arranged to coöperate with similar elements of a second section to form a hinge. It further consists in a longitudi- 50 nally extending sheet of metal welded to said bar and curved below the edge portion of the opposite hood section to form a trough for receiving water that may leak through the joint.

55 In the drawings, Figure 1 is a perspective

view showing a preferred embodiment of the invention. Fig. 2 is a similar fragmentary view, the sections being detached from one another and parts being broken away. Fig. 3 is a fragmentary plan view more 60 clearly showing the alinement of the hinge elements. Fig. 4 is an enlarged fragmentary plan view corresponding to Fig. 3.

As is usual in hood construction, the hood preferably includes top sections 1 and side 65 sections 2 pivoted thereto. The metal of the meeting edges of the top sections is bent downwardly at substantially right angles to form flanges 3 to the inner surfaces of which are welded reversely arranged reinforcing 70 bars 4 that extend the entire length of the hood. At one end the bars are offset upwardly and toward the opposite top section and shaped to form pintles or studs 5, while the opposite ends of the bars are similarly 75 offset upwardly and toward the other section and shaped to form sockets 6 for the pintles of the opposite top section. Referring particularly to Figs. 3 and 4, it will be seen that the flanges 3 terminate at points 80 slightly inward from the ends of the sections, thus forming adjacent the sockets, shoulders 8, and that in offsetting the pintles there are formed inclined shoulders 9. When the hood is closed or nearly closed 85 these shoulders are alined, from which it follows that, should it be attempted to draw the sections apart in either direction longitudinally of their pivotal axis, the corresponding shoulder 8 will strike the corre- 90 sponding shoulder 9. A portion of the metal at the point where the sockets merge with the rest of the reinforcing bars is cut away, as indicated at 10, to afford clearance for the shoulders 9 when either half of the 95 hood is swung upwardly about the other half, and it is only necessary, therefore, in order to detach the sections from one another, to swing the section upwardly until the shoulders 9 pass out of the alinement 100 with the shoulders 8, whereupon the sections may immediately be separated by relative movement longitudinally of the pivotal axis.

In order to prevent water from dripping 105 through the seam at points between the ends of the hood, a sheet metal trough or gutter may be used. As shown, this trough is formed of a flange 15, up-turned along the inner face of one of the bars 4 and welded 110

thereto, from the lower edge of which the metal is curved laterally under the edge of the opposite section at 16.

In use the ends of the sockets 6 rest on suitable bearing straps (not shown) located rearwardly of the radiator and forwardly of the cowl, as will be readily understood, and retaining straps may be provided for holding them in position.

10 The construction is inexpensive, both in material and in the manipulative processes involved in its manufacture. When in position on the car the upper surface is smooth and unbroken, thus conforming well to the 15 lines of the latter, and the absence of pins or other third members which must be withdrawn or which are liable to become shaken loose, together with the ease whereby the sections may be connected or disconnected, 20 renders the whole device unusually reliable and convenient.

The actual details of construction may, of course, be varied considerably without departing from the spirit of the invention, 25 and I do not, therefore, wish to be limited except as indicated by the subjoined claims.

I claim:—

1. A hood comprising a section having a downturned edge forming a web, a reinforcing member secured to and extending longitudinally along the lower portion of said web, said member rising near the ends of the web and forming alined pivot elements, a second hood section, and means carried 35 thereby and coöperating with said pivot elements whereby a pivotal connection between said sections is formed.

2. An automobile hood comprising two sections hinged to each other to swing outwardly relative to each other, one of the sections having an upwardly and laterally offset pintle projecting therefrom, the other section having an upwardly and laterally offset socket member projecting therefrom 45 which forms a bearing for said pintle, the parts being so constructed and arranged that the sections are interlocked against relative movement longitudinally of the axis of said hinge when in normal position but are free 50 for such movement when one of the sections is swung upwardly in respect to the other.

3. An automobile hood comprising sheet metal top sections having their meeting edges turned downwardly to form flanges, 55 bars rigidly secured to the sections along the inner sides of said flanges, said bars having coöperating pivot forming elements at the ends thereof beyond the corresponding ends of the sheet metal whereby a smooth 60 upper surface is presented.

4. An automobile hood comprising sheet metal sections having downturned meeting edges, bars rigidly secured to the sections along the inner sides of said flanges, said 65 bars having at their ends complementary in-

terlocking pivot forming elements one of which is offset both upwardly and laterally from the corresponding edge of the sheet metal.

5. An automobile hood comprising a pair 70 of sheet metal top section plates, pivot forming means connecting said plates whereby they may be swung upwardly in respect to each other, said pivot forming means including a pintle fixed to one of the plates 75 and projecting outwardly beyond the edge thereof, said pintle being offset upwardly and laterally, said pivot forming means also including a socket member fixed to the other plate and projecting outwardly beyond the 80 edge thereof for receiving the pintle, the parts being so constructed and arranged that the pintle strikes the second plate upon movement relative thereto longitudinally of the pivot when the hood is in normal position, but is free for such relative longitudinal movement when the first plate is swung 85 upwardly in respect to the second plate.

6. An automobile hood comprising a pair 90 of pivotally connected sheet metal section plates having meeting edges, said plates being free from each other from end to end of said edges, and coöperating interlocked alined pivot forming means projecting from said plates at the opposite ends of said edges. 95

7. An automobile hood comprising a pair 100 of sheet metal section plates having meeting edges, and means rigid with said plates and extending outwardly therefrom beyond the ends of said edges for forming coöperating elements of alined pivots, said coöperating elements constituting the sole means for connecting the sections.

8. An automobile hood comprising a pair 105 of sheet metal top plates having meeting edges, and means rigid with said plates for forming alined pivotal connections therefor, one at either end thereof, said means comprising a pair of reversely arranged bars, one rigid with one of the plates and the other 110 rigid with the other plate, each bar having at one end a socket and at the other end a pintle, the parts being so constructed and arranged as to form an interlocking connection when the hood is in normal position. 115

9. An automobile hood comprising a pair 120 of sheet metal top plates having downturned meeting flanges, pivot bars secured to the plates along the inner sides of said flanges, and a longitudinally extending sheet metal trough secured to one of the pivot bars and projecting under the other bar to intercept water that passes through between the flanges.

10. An automobile hood comprising a pair 125 of sheet metal top plates having downturned meeting flanges, pivot bars welded to the inner sides of said flanges, and a longitudinally extending sheet metal trough welded to one of the bars on the side thereof most 130

remote from said flanges and projecting under the other bar to intercept water that leaks through between the flanges.

11. In a hood, the combination of two sections one of which has a downturned edge portion forming a web, a pivot rod having a depressed central portion extending longitudinally of the lower edge of the web, said rod also having alined end portions located at a higher level, and means carried by the other section coöperating with said end portions to form a pivotal connection between said sections.

12. A hood comprising two pivotally connected sections one of which has a downwardly extending web terminating a short distance from each end of the section, a pivot

rod having a depressed central portion extending along the lower margin of said web, said rod having alined end portions located at a higher level, and means fixed to the other section and coöperating with said end portions for forming a pivotal connection between the sections.

13. A hood comprising two sections one of which includes a U-shaped combined reinforcing bar and pivot rod, said section having a downwardly extending web fixed to the central portion of the bar whereby a girder or truss is formed, and means associated with the alined end portions for forming a pivotal connection with the other section.

BARNEY BERNARD.
